By David O. Barnell

Attorney.

UNITED STATES PATENT OFFICE.

GEORGE CHRISTIANSEN, OF OMAHA, NEBRASKA.

BUCKLE AND WRIST-STRAP.

1,390,761.

Specification of Letters Patent. Patented Sept. 13, 1921.

Application filed May 3, 1920. Serial No. 378,550.

To all whom it may concern:

Be it known that I, GEORGE CHRISTIANSEN, a citizen of the United States, and a resident of Omaha, in the county of Douglas and 5 State of Nebraska, have invented certain new and useful Improvements in Buckles and Wrist-Straps, of which the following is a specification.

My invention relates to buckles and wrist-10 straps of the class especially adapted for use in holding a watch or like article upon the wrist. It is the object of my invention to provide a simple and inexpensive buckle especially adapted for use with a trans-15 versely corded ribbon or fabric strap to form wrist-attaching means for a watch or the like, for use as a bracelet. A further object of my invention is to provide a buckle of this class having specially formed means for 20 engaging the ribbon or strap without injury thereto, but so as to effectually prevent slipping of the buckle relative to the ribbon, when the parts are in use. A further object of my invention is to provide a buckle of 25 this class which may be readily engaged with and disengaged from any intermediate portion of the ribbon or strap, by the use of one hand only, and without liability of dropping the watch with which the strap 30 and buckle are used. A further object of my invention is to provide a buckle of this class having means for effectually preventing the same from assuming a diagonal position with reference to the ribbon, when the 35 device is in use, and to prevent the buckle being disengaged from the ribbon or strap by lateral movement relative thereto, except by a deliberate act of the wearer. This application is in part a continuation of my 40 application for watch bracelet, filed Aug. 31, 1917, Serial No. 189,095.

In the accompanying drawings Figure 1 is an end view of a watch bracelet formed with a buckle embodying my invention, and 45 a ribbon arranged in accordance therewith, Fig. 2 is a detail bottom or inner side view of the buckle, with a portion of the ribbon attached thereto, Fig. 3 is a plan or outer side view of the buckle alone, Fig. 4 is a 50 longitudinal section of the buckle and ribbon, and Fig. 5 is a detail transverse section of the buckle on the line 5—5 of Fig. 2.

Referring to Fig. 1 of the drawings, there is illustrated a watch 6 having at opposite 55 sides thereof loops or bows 7 for connection with a strap or ribbon to attach the same in

the form of a bracelet upon the wrist of the user. I preferably employ a fabric strap or ribbon 8 which is corded or transversely ribbed, as indicated in Figs. 2 and 4, and 60 one end of said ribbon is connected in any suitable way with one of the bows 7 of the watch. The body or intermediate portion of the ribbon passes slidably through the second bow 7, and the second end of the ribbon 65 is formed into a loop 9 for connection with the buckle.

The buckle is formed from a single plate of metal, and has a flat approximately rectangular body-portion 10. On said body 70 adjoining one end thereof, which for convenience of description will be designated as the rear end, there are rounded laterally projecting lugs 11, and between said lugs there is a transverse slot 12 of which the 75 rearward side is substantially closed by two fingers 13, the latter extending inwardly from the sides of the body, and the adjacent ends thereof being but slightly separated. One of the fingers 13 is preferably longer 80 than the other, for convenience in connecting the buckle with the loop 9 at the end of the ribbon 8. In attaching the buckle to the loop 9, the longer of the fingers 13 is inserted in the loop at one side thereof, the end-portion 85 of the loop being passed through between the ends of the fingers, and crowded into the slot 12 until the second finger can enter the opposite side of the loop, after which the loop is flattened out so as to lie 90 smoothly in the slot 12, of which the width is substantially the same as that of the ribbon. Obviously, the ribbon can be detached from the buckle by crowding the loop into that end of the slot 12 adjoining the longer 95 finger 13, and then slipping one edge out through the opening between the ends of the fingers.

At the front end of the body 10 there is a transverse slot 14 which is open at one 100 end, the front side of the slot being formed by the rear edge of a finger 15 which is joined to the body at the closed end of the slot. The front edge of the finger 15 is rounded transversely as shown in Figs. 2 105 and 3, and at the rear edge of the finger there is a thin projecting portion or lip 16 which extends partially across the slot 14. Opposite said lip 16, at the front edge of the body 10 there is a second lip 17, which 110 projects downwardly, or inwardly with reference to the position of the buckle when

- 2
- the same is in use. At the lateral edges of the body 10 are flanges 18 and 19, of which the longitudinal edges are slightly hooked or turned inwardly as shown in Fig. 5.
- 5 The flange 18 terminates at the rear edge of the slot 14, but the flange 19 is longer and extends past the closed end of said slot 14, thus strengthening the connecting portion between the body 10 and the finger 15.
- 10 When attached to the loop 9 at the end of the ribbon, the buckle prevents said loop being pulled through the bow 7 of the watch, and thus maintains the bracelet formation, so that after being slipped over the hand of
- 15 the user there is no possibility of dropping the watch while adjusting the bracelet to fit upon the wrist. The adjustment of the bracelet is readily effected by the use of one hand only, the operation being as follows:
- 20 The lugs 11 at the sides of the buckle are caught between the thumb and forefinger, the ribbon is pulled through the watch-bow 7 until the desired tightness upon the wrist is attained, and the end of the finger 15 is
- 25 then inserted beneath the ribbon, so that the latter passes into the slot 14 of the buckle. Upon releasing hold of the buckle, the pull of the ribbon at the rear end thereof draws the body down into parallelism
- 30 with the engaged portion of the ribbon-body, as shown in Figs. 1 and 4. When in this position the lips 16 and 17 enter the transverse grooves or corrugations of the corded ribbon and effectually prevent slipping of the ribbon through the buckle. At
- 35 the same time the flanges 18 and 19 embrace the sides of the ribbon and prevent the buckle being twisted to a diagonal position relative to the ribbon-body.
- 40 To release the buckle, it is merely necessary to grasp the same at the lugs 11, as before, pulling the rear end of the buckle outwardly until it is approximately perpendicular to the engaged part of the rib-

bon, and then moving the buckle laterally 45 to withdraw the finger 15 from beneath the ribbon. The lugs 11 greatly facilitate the release of the buckle, by readily permitting the same to turn pivotally between the thumb and finger, when pulling the rear 50 end of the buckle outwardly from the ribbon, and thus automatically turning the buckle-body to a position at which the lips 17 and flange 18 do not interfere with the lateral releasing movement. 55

Now, having described my invention, what I claim and desire to secure by Letters Patent is:

1. A buckle comprising a flat body portion having at one end means for connection 60 with the end of a strap, laterally extending lugs at said end of the body, there being at the opposite end of the body a finger spaced therefrom to form a transverse slot open at one end, strap-engaging lips at each 65 side of said transverse slot, and longitudinal inturned flanges at the sides of the body for the purpose described.

2. An adjustable wrist-strap comprising a ribbon adapted to have one end attached 70 to one of a pair of strap bows and have its other end slidably through the other one of such bows to form a loop, a buckle having one end connected with said loop, the opposite end of the buckle having a transverse 75 slot open at one end whereby to pass transversely over any intermediate portion of the ribbon, there being fixed lips at the edges of said slot engageable with the ribbon to prevent relative longitudinal movement of 80 the buckle thereon, there being flanges at the sides of the buckle adapted to embrace the sides of the ribbon when the same and the buckle-body are in parallelism, and lugs at the sides of the buckle adjoining the first-named end thereof, for the purpose described. 85

GEORGE CHRISTIANSEN.
